UNITED STATES PATENT OFFICE

165,195

AUTOMOBILE

Peter Schlumbohm, New York, N. Y.

Application July 28, 1950, Serial No. 11,470

Term of patent 14 years

(Cl. D14—3)

To all whom it may concern:

Be it known that Peter Schlumbohm, a citizen of the United States of America, residing at New York, in the county of New York and State of New York, has invented a new, original, and ornamental Design for an Automobile, of which the following is a specification, reference being had to the accompanying drawing, forming part thereof.

Fig. 1 is a side view of an automobile, showing my new design.

Fig. 2 is a top view of the automobile shown in Fig. 1.

Fig. 3 is a front view of the automobile shown in Fig. 1.

Fig. 4 is a rear view of the automobile shown in Fig. 1.

Fig. 5 is a perspective view of the automobile shown in Fig. 1—Fig. 4.

I claim:

The ornamental design for an automobile, as shown.

PETER SCHLUMBOHM.
